UNITED STATES PATENT OFFICE.

THOMAS M. PRICE, OF RALEIGH, NORTH CAROLINA.

EQUALIZING WEDGE ADJUSTER.

Application filed July 30, 1925. Serial No. 47,020.

To all whom it may concern:

Be it known that I, THOMAS M. PRICE, a citizen of the United States, residing at Raleigh, in the county of Wake and State 5 of North Carolina, have invented certain new and useful Improvements in Equalizing Wedge Adjusters, of which the following is a full, clear, and exact description.

This invention relates to wedges of the 10 wear compensating type such as are in common use in the driving boxes of locomotives and the like, and has special reference to means for supporting the wedge in such manner as to prevent jamming of the same 15 between the driving box and the engine pedestal.

The purpose of wedges of the present type is to prevent looseness and pounding of the 20 box within the walls of the engine frame, which is often encountered because of great strains due to heavy grades and curves which tends to work the wedge out of tight engagement with the box and pedestal. It has been proposed to overcome this difficulty 25 by providing a screw bolt for adjusting the box to proper position, but this adjustment can only be made while the engine is at a standstill and it frequently occurs that the wedge will work loose during a long run 30 and cause a pounding of the parts before such an adjustment can be made. Devices have therefore been provided in which a spring has been employed for forcing the wedge tightly into position between the driving 35 box and pedestal at all times. With such a construction however the wedge becomes jammed in place so as to prevent the necessary vertical play between the driving box and the engine pedestal.

40 It is therefore an object of the present invention to overcome the foregoing difficulties in adjustment of these wedges by providing a floating support for the wedges whereby the latter is held in proper position 45 with relation to the driving box and pedestal and yet will not become jammed in place nor work loose so as to cause a pounding of the parts.

A further object of the invention resides 50 in the provision of such a mounting for the wedge which may be adjusted from time to time as desired so as to bring the wedge into proper position with respect to its co-operating parts.

55 Other objects and advantages of the invention will be apparent from the following

description when taken in connection with the accompanying drawings, in which:

Figure 1 is a fragmentary view of an engine pedestal and driving box and showing 60 the equalizing wedge adjuster in position thereon; and

Figure 2 is an enlarged sectional view of the equalizing adjuster taken on line 2—2 65 of Figure 1.

Referring to the drawings more in detail the numeral 1 indicates the usual engine pedestal provided with the pedestal binder 2 and in which is mounted for vertical play 70 the driving box 3.

In the usual construction of these boxes it is usual to provide a suitable wedge 4 by means of which lateral movement of the driving box with respect to the engine pedestal is prevented, thereby eliminating 75 pounding of these parts during the operation of the locomotive. As hereinbefore stated it is an object of the present invention to provide a mounting for this wedge 4 so as to hold the same at all times in 80 proper position with respect to the driving box and yet prevent the same from jamming between the driving box and engine pedestal so as to prevent the natural movement between these parts. To this end the 85 wedge 4 is mounted as indicated by numeral 6 upon the vertically extending rod 7 which extends through and is slidably mounted in the pedestal binder 2. Secured to the lower edge of the binder 2 is a cylindrical casing 8 through which the rod 7 also extends.

Formed upon the rod 7 is a collar or a button 9 which is so located with respect to the ends of the rod 7 as to be positioned within the casing 8. This collar 9 is provided for the purpose of cooperation with a pair of coil springs 10 and 11 which are disposed within the casing 8 and upon opposite sides of the collar 9. Spring cups 12 and 13 are also mounted within the casing 100 8, spring cup 12 being interposed between the pedestal binder 2 and the upper end of spring 10 while the lower end of the coil spring 10 is in engagement with the upper surface of the collar 9. The spring cup 13 is screw threaded as indicated by numeral 14 for threaded engagement with the aperture in the bottom of the casing 8 and this cup receives the lower end of the coil spring 11 whose other end is in engagement with the 105 bottom surface of the collar 9. A jam nut 15 is provided for locking the spring cup

13 in its adjusted position. It should also be noted that the lower end of the rod 7 is screw threaded for the reception of a nut 16, and it will be obvious that should the 5 wedge 4 become jammed between the driving box and engine pedestal the same may be readily withdrawn by screwing the nut 16 up against the lower surface of the spring cup 13.

10 From the foregoing description taken in connection with the accompanying drawings it will be observed that by means of the opposed springs 10 and 11 which cooperate with the interposed collar 9 that the wedge 15 4 is resiliently supported in a substantially floating position between the driving box and engine pedestal and thus maintained in proper cooperative relation with these parts without danger of jamming when in use. It 20 will also be apparent that if adjustment of the wedge is necessary due to wear upon the driving box the same may be accomplished by merely loosening the jam nut 15 and rotating the spring cup 13 the desired 25 amount, and again moving the jam nut 15 to locking position.

30 In accordance with the patent statutes I have described what I now believe to be the best embodiment of the invention, but I do 35 not wish to be understood thereby as limiting myself or the scope of the invention, as many changes and modifications may be made without departing from the spirit of

the invention; all such I aim to include in the scope of the appended claims.

What I claim as new and desire to secure by Letters Patent is:

1. A support for driving box wedges including a slidably-mounted rod on which said wedge is secured, an abutment on said rod, and a pair of opposed spring devices associated with said rod and abutment. 40

2. A support for driving box wedges including a slidably-mounted rod on which said wedge is secured, an abutment on said rod, a pair of opposed spring devices associated with said rod and abutment, and means for longitudinally adjusting the position of said rod and wedge. 45

3. A support for driving box wedges including a slidably-mounted rod, a collar on said rod, and a pair of coil springs engaging opposite sides of said collar. 50

4. In a device of the character described, the combination with the driving box and engine pedestal, of a vertically disposed wedge between the box and pedestal, a slidably-mounted rod on which said wedge is secured, a collar on said rod, a pair of coil springs disposed on opposite sides of said collar and cooperating therewith, and a threaded spring cup for varying the tension on said springs and the position of said rod and wedge. 60

T. M. PRICE.
